SAFETY DEVICE FOR PRESS

Louis F. Archer, Warwick, R.I., assignor to Mays Manufacturing Company, Inc., a corporation of Rhode Island

Filed Aug. 7, 1958, Ser. No. 753,798

2 Claims. (Cl. 100—53)

This invention relates to a safety device for a power press.

A power press of the type of which the present invention is concerned usually has a ram which makes one complete reciprocation at each cycle of operation and then comes to rest with the ram in the elevated position. The ram is usually driven through a motor belt drive including a clutch mechanism which is pneumatically controlled. A pair of normally closed valves are positioned in the air supply conduit to the press and these are arranged in series so that both valves must be moved to the open position for supplying air pressure to operate the clutch. The valves are manually operated each by a pivoted lever, thus occupying both hands of the operator to move to open relation and providing a desirable safety measure.

It has, however, been found that at times through valve failure and the like, air pressure escaping past the valves will build up in the portion of the conduit leading to the clutch control or the clutch control will otherwise fail and actuate the clutch setting the ram in motion and creating a very serious condition.

An object of the invention is to provide a safety device which will operate to provide for a positive arresting of any accidental downward movement of the ram upon valve failure in the air control mechanism of the press.

Another object of the invention is to provide a safety device which upon being moved to inoperative position will be reset in ram blocking relation by the downward movement of the ram.

A more specific object of the invention is to provide a safety device wherein a ram blocking means will be arranged in a way to be removed from blocking relation during the manual operation of moving the valves to open position.

With these and other objects in view, the invention consists of certain novel features of construction as will be more fully described and particularly pointed out in the appended claims.

In the accompanying drawings:

Figure 1 is a front elevational view of a fragmentary portion of a power press embodying my invention;

Figure 2 is an edge elevation of a fragmentary view of the press of Figure 1; and

Figure 3 is a sectional view taken along line 2—2 of Figure 1 with certain parts omitted for clarity.

Referring to the drawing for a more detailed description of the invention, 10 designates generally a power press, only so much of which has been shown as is believed necessary for a clear understanding of the present invention. The press 10 comprises the usual work shelf 11 which is supported on legs 12. Spaced uprights 13 rise from the shelf 11 and are provided with slides 14 in which a ram 15 is mounted for vertical reciprocation. The shelf provides a support for the lower die portion 16, and the upper die portion 17 is secured to the ram. The ram is operated by known drive means (not shown) which usually includes a motor driven endless belt driving a pulley which is connected to the ram by a one revolu-

2

tion type clutch mechanism usually referred to as a dog which automatically becomes disengaged at each revolution to disconnect the drive to the ram. The above drive means is standard, well known to workers in the art, and 5 is no part of the present invention.

In the present instance the said clutch is pneumatically controlled and for this purpose the press is provided with an air pressure conduit generally designated 18 which leads to the said clutch. A pair of manually operated 10 valves 19, 20 are positioned in series in conduit 18 and are arranged to be held normally closed. The valve 19 is positioned at one side of the press and the valve 20 is at the opposite side of the press. The valve 19 controls the air flow to valve 20 and is manually moved to open 15 position by a lever 21, see Figure 2, which is pivotally mounted as at 22 on a bracket 23 which is also utilized for mounting the valve 19 in place. The lever 21 extends forwardly from the pivot 22 and overlies the stem 19' of the valve 19. The valve is of known type in which the 20 inward movement of the stem 19' will move the valve to open position and will automatically be moved to the closed position thereof when a force is removed therefrom. Thus upon pressing the lever 21 downwardly about the pivot 22, the lever will engage the stem 19' to move 25 the same inwardly to move the valve 19 to open position so as to open the passageway therethrough to allow a flow of air under pressure from conduit portion 18a to conduit portion 18b. Upon release of the lever 21, the stem 19' will automatically return to the closed position thereof and also swing lever 21 in the other direction to initial position.

It will be seen that air pressure will flow to closed valve 20 and be there blocked against passage into conduit portion 18c leading to the said clutch mechanism of the press. The valve 20 is similarly moved to open position by a lever 24 which is similarly swung to engage and move the valve stem 20' to move the valve to open position so as to open the passageway through valve 20 for a flow of air pressure through conduit portion 18c. It will be apparent from the above that both valves 19 and 20 need to be moved simultaneously or nearly so for connecting the ram to the driving means thereof. Thus, moving the valves 19, 20 to open position requires both hands of the operator to be occupied and consequently removed from 45 the vicinity of the dies of the press during the downwardly stroke of the ram.

As previously mentioned, a valve failure such as a leak may occur and cause a very serious and dangerous condition to develop in that pressure builds up in the portion 50 of the air conduit to the ram control to a degree to set the ram in motion. In some instances a failure in valve 19 may allow a pressure to build up in conduit portion 18b and movement of only lever 24 may set the ram in motion. In order to guard against such an event and prevent other 55 uncontrolled downward movements of the ram, I provide an obstruction which is arranged to be held normally in the path of the downward stroke of the ram. The said obstruction in the present instance is a bar or post 25 (see Figure 3) which is pivotally mounted as at 26 to a 60 block 27 suitably secured to the shelf 11. The post extends vertically with the upper end thereof beneath the ram and closely adjacent the lower edge thereof. Thus unless the post is removed, the same will be engaged by the ram on the downstroke thereof and there held against 65 further movement. A shoulder 28 is provided at the upper end of the post which is biased into engagement with the rear side of the ram by a pull spring 29. One end of the pull spring is fastened to the post 25 as at 30 and the other end of the spring is anchored to a pin or 70 the like 31 held stationary on the plate 11 or at some other suitable location on the press.

A latch 32 is pivotally mounted on post 25 as at 33 and

extends rearwardly therefrom. The latch is spring biased for counter clockwise rocking (as viewed in the drawing) by a pull spring 35 which is fastened at one end thereof to the latch and at the other end thereof to an anchor pin 36 which projects from the block 27. A keeper bar 37 projects upwardly from block 27 into engagement with the lower edge 38 of the latch. An elongated notch or recess 39 is provided in the edge 38 and extends from adjacent the pivot 33 to adjacent the location at which the keeper bar 37 engages the edge 38 when the post 25 is in the ram blocking relation. The post 25 may be removed from blocking relation under proper control of the operator.

To this end the pivot 22 is extended as at 22' and carries a bell crank 40 having a roller 41 secured at the free end thereof which extends into engagement with the post 25 as best seen in Figure 3. The pivot 22, to be hereinafter referred to as a pivot shaft, is fixed to lever 21 and arranged to be rotatable in the bracket 23. Thus rocking the lever 21 will also axially turn shaft 22 and rock crank 40 clockwise as seen in Figure 3, roller 41 swinging post 25 out from beneath the lower edge of ram 15 as shown in broken lines. This will carry the latch 32 rearwardly and the keeper bar 37 will ride into the notch 39 and be held engaged against edge 39' through action of spring 35 and pull spring 29. Thus the post will be locked in the inoperative position thereof.

As already mentioned, both hands of the operator will be occupied in pressing down the levers 21 and 24 to set the ram in action. In practice the operator presses down on both levers simultaneously and then releases the levers prior to the ram completing its cycle of operation. In the inoperative position of the post 25, the forward portion or nose 34 of the latch 32 will be in the path of the down stroke of the ram to be engaged thereby which will rock the latch 32 in the opposite direction and disconnect the notch 39 from the bar 37. Generally, the operator releases levers 21, 24 after the ram has partially completed its cycle of operation and therefore roller 41 will be free of the post 25 by the time the ram begins its upward stroke. Accordingly, the pull of spring 29 will be tending to rock post 25 to a vertical attitude and will carry latch 32 to position notch 39 forward of bar 37.

From the foregoing it will be apparent that post 25 will

be held in ram blocking position at all times during inaction of the press so as to block an accidental downward stroke of the ram in the event of valve failure or other cause. Thus the press may be loaded and unloaded in safety at all times. Since operation of the press requires the use of both hands of the operator at a location removed from the path of reciprocation of the ram, post 25 may not be removed by the operator without deliberate knowledge. Thus the operator will have a sense of security in operating the press, which is very desirable.

I claim:

1. In a pneumatically controlled power press having a ram mounted for vertical reciprocation, an air conduit for said press, a pair of valves in said conduit, said valves being positioned in series in said conduit and normally held closed, a rockable lever for each of said valves operatively connected thereto to operate the valves, a bar pivotally mounted on said press in such a manner as to extend generally vertical beneath the ram in position to be engaged thereby to block the downward stroke thereof, a crank connected to one of said levers and extending into engagement with said bar and rockable about an axis parallel to the pivot of said bar by the said levers to which it is connected to move said bar from ram blocking relation, a movable latch carried by said bar, and a relatively fixed keeper positioned at a location to engage said latch upon moving said bar from ram blocking relation and retain said bar out of blocking relation, a spring for urging said bar to ram blocking position, said latch having a portion in the path of movement of said ram to be engaged by the ram and release the latch from the keeper after the ram has moved a predetermined distance downwardly.

2. In a pneumatically controlled power press as set forth in claim 1 wherein said latch is spring urged into engagement with said keeper.
